Primary Examiner—Susan J. Lucas

[57] CLAIM

The ornamental design for a suspended luminaire, as shown and described.

DESCRIPTION

FIG. 1 is a perspective view of a first embodiment of our new design;

FIG. 2 is a side elevational view of the first embodiment;

FIG. 3 is a top plan view of the first embodiment;

FIG. 4 is a bottom plan view of the first embodiment;

FIG. 5 is a perspective view of a second embodiment of our new design;

FIG. 6 is a side elevational view of the second embodiment;

FIG. 7 is a top plan view of the second embodiment; and,

FIG. 8 is a bottom plan view of the second embodiment.

The broken lines are shown for illustrative purposes only and form no part of the claimed design.
